UNITED STATES PATENT OFFICE

2,081,855

METHOD FOR INCREASING LUBRICATING
OIL YIELDSFred G. Fellows, Ponca City, Okla., assignor to
Continental Oil Company, Ponca City, Okla.,
a corporation of Delaware

Application January 28, 1935, Serial No. 3,697

4 Claims. (Cl. 196—73)

My invention relates to a method for increasing lubricating oil yields.

This application is a continuation in part of my co-pending application, Serial No. 558,765, filed August 22, 1931, for "Method and apparatus for increasing lubricating oil yields".

Oil refiners find that, at certain periods, lubricating oil demands increase while light oil demands decrease. This renders it desirable to operate refineries for the maximum production of lubricating oils.

A distillation plant is usually designed for a crude oil having characteristics falling between certain limits. It frequently happens that the supply of crude oil having the characteristics for which a distillation plant has been designed, becomes exhausted. If a crude oil having different characteristics is processed in a plant designed for another crude, the yields will be low, and if the processing conditions are attempted to be adjusted to increase these yields, other difficulties will arise, and it will be found that cracking and carbon depositions may take place. For example, a plant was designed for running Seminole Osage crude for producing cylinder stock in an atmospheric, single flash operation. Similarly, another plant was designed for producing cylinder stock from Seminole Osage crude in a two-stage atmospheric and vacuum distillation unit. In operating these units with the Seminole Osage crude, satisfactory yields were obtained, the stocks were of good character and were produced with ease. The units could be kept on stream for considerable periods without cleaning. When the supply of Seminole Osage crude was not available, it was attempted to run a Kansas Crude in the same units. Difficulties immediately arose. The yields were low and the stocks produced were of poor quality. Considerable difficulty was encountered in that the towers coked after a short period of operation. It will be obvious that inasmuch as crude oils vary in price it is desirable to be able to run a unit with various crudes and yet produce the desired results.

One object of my invention is to provide a method enabling refiners to secure a lubricating oil yield, when desired, from crude oils normally not adapted to give such yields.

Another object of my invention is to provide a charging stock from a virgin crude having a preponderance of light fractions, enabling it to be processed in units which were designed for crude oils of different characteristics.

Another object of my invention is to provide a

process whereby crude oils of differing characteristics may be economically processed in order to obtain desired lubricating oil yields.

In general, my invention contemplates the building of a synthetic crude by altering the equilibrium flash vaporization temperature of the virgin crude. I accomplish this by adding to the virgin crude a percentage of topped crude having a higher equilibrium flash vaporization point, so that the resulting equilibrium flash vaporization point will allow the material which it is desired to recover, to be vaporized without causing cracking to take place, and at the same time supply sufficient heat to the fractionating column so that sufficient reflux medium can be used to produce streams of proper specifications.

It is known that crude oils bearing a large percentage of heavy ends require a higher flash temperature in order to secure the same percentage of overhead lubricating oil products than do crude oils carrying a preponderance of light ends.

In the prior art, United States patent to Peterkin et al., No. 1,710,240, discloses the addition of low boiling materials to crude oils which are deficient in the same, in order to obtain the carrying effect of the easily volatile, lighter ends.

United States patent to Coubrough, No. 1,911,993, dated May 30, 1933, discloses the adding of heavy material, such as non-volatile asphalt, to the crude oil as a heat-carrying medium. Coubrough adds a heavy material of such character that the boiling point of the desired constituents of the crude oil is not sufficiently affected. He makes no attempt to alter the equilibrium flash vaporization temperatures, but employs the heat-carrying material to supply heat in much the same manner as employed in a heating coil for reboiling the heaviest fraction of reflux condensate. Moreover, none of the heavy material added by Coubrough is vaporized and taken overhead.

In the accompanying drawings which form part of the instant specification and which are to be read in conjunction therewith, and in which like reference numerals are used to indicate like parts in the various views;

Figure 1 is a diagrammatic view of a two-stage atmospheric and vacuum distillation unit.

Figure 2 is a diagrammatic view of an atmospheric, single flash lubricating oil unit.

Figure 3 is a graph showing curves obtained by plotting the slopes of the true boiling point curves from the 10% to the 70% over points against the percentages over at intersections between flash

distillation curves and true boiling point batch distillation curves.

Figure 4 is a graph showing a curve obtained by plotting the slope of the true boiling point curve from the 10% to the 70% over points against the slope of the flash distillation curve from the 10% to the 70% over points.

Figure 5 is a graph showing curves obtained by plotting the percentage distilled overhead against temperature degrees Fahrenheit (true boiling point curves).

The curves in Figure 6 are equilibrium flash vaporization temperature curves showing percentages obtained overhead at temperatures degrees Fahrenheit.

By the term "equilibrium flash vaporization temperature" is meant the temperature to which a hydrocarbon oil must be heated in order to vaporize a given percentage of oil when the heated mixture is flashed and at which temperature the flashed vapors are in equilibrium with all remaining liquid. It will be appreciated that due to the ease with which hydrocarbon oils are decomposed at high temperatures, the desired percentage cannot be obtained in some cases without cracking or decomposing certain fractions. Sometimes this difficulty may be overcome by lowering the equilibrium flash vaporization temperature below the cracking temperature by adding more volatile hydrocarbons to the charging stock, thus taking advantage of the carrying effect of the lighter ends. An example of this has been pointed out above in Peterkin et al. Patent No. 1,710,240. In other cases, however, the difficulty is not overcome in this manner, because cracking is not only a function of temperatures, but of time, as well.

By way of example, assume that I desire to distill out the lubricating oil fractions of a light crude which contains a small percentage of such fractions. In attempting to secure a yield of such products by distillation, it is discovered that the volume of the heavy or lubricating oil fractions is so small that the liquid refluxing down through the tower and being withdrawn from the side streams and the bottom of the tower has a low velocity and therefore remains in the tower for such a long period of time that cracking ensues.

The amount and nature of the hydrocarbon oil to be added to the charging stock to obtain an increased equilibrium flash vaporization temperature is determined in the following manner:

(a) The time and temperature relationship to cracking of the heavy ends which it is desired to recover, is determined in the laboratory by bomb tests.

(b) The volumetric capacity of the pipe still and flash tower is known. From this volume and the time and temperature relation to cracking, I am enabled to determine the amount and nature of oil which must be present in the charging stock to prevent cracking at varying temperatures.

(c) For co-related relationships between laboratory true boiling point curves and equilibrium flash curves, the equilibrium flash vaporization temperature can be determined for a mixture which will satisfy (b) above, and in all cases will be higher than the equilibrium flash vaporization temperature of the original hydrocarbon oil to be distilled.

An example of such determination is as follows:

75 An analysis of a particular hydrocarbon oil

disclosed the presence of desired "heavy ends" which could be used for lubricating oil production. The equilibrium flash vaporization temperature of this oil was calculated to be 705° F. when obtaining the total quantity of the desired heavy ends. It was found from laboratory bomb tests that the desired heavy ends would crack at a temperature of 700° F. or above, if subjected to such temperature for 7 minutes or more. Calculations revealed the fact that the volume of desired heavy ends will be so small that the length of time it would take for them to flow through the tower would be approximately 7 minutes. It is obvious that if this oil were processed in an attempt to recover the desired heavy ends, cracking would ensue. It was also found that the desired heavy ends would not crack at higher temperatures if the time period at which they were held at the higher temperatures were reduced. For example, it was found that cracking would not ensue if the oil was held at a temperature as high as 850° F., provided the time period during which the oil was subjected to this temperature did not exceed five minutes. If the oil could be processed so that the desired heavy ends would remain in the tower not more than five minutes, a temperature of 850° F. could be used without cracking. To obtain this short a time period it was necessary to increase the percentage of heavy ends from 28% to 40%. Having determined the amount of heavy ends required to increase the percentage of heavy ends in the mixture to 40%, it is necessary to determine whether or not the equilibrium flash vaporization temperatures of the blended material containing 40% of heavy ends is above the critical cracking temperature.

Figures 3, 4, 5 and 6 show the co-related relationship between laboratory true boiling point curves and equilibrium flash vaporization temperature curves. The use of these curves will be apparent from the following example.

In Figure 5 the vapor temperatures are plotted as ordinates against liquid-volume percent distilled as abscissæ. The following data is read from the true boiling point curve of the initial stock:

	° F.	50
Temperature of 70% vaporized	790	50
Temperature of 10% vaporized	230	
Temperature of 50% vaporized	605	

The slope between the 10% and 70% points obtained as follows:

$$\frac{790 - 230}{70 - 10} = \frac{560}{60} = 9.3^{\circ} = \text{F. per percent}$$

From Figure 4 it will be seen that the slope of the flash curve equals 6.6. From Figure 3, the per cent over at the intersection between the true boiling point curve and the flash curve is 35%. From Figure 5 the temperature at 35% is read as 465° F. A point on the flash curve and its slope being established, the flash curve is drawn in Figure 6.

In a similar manner, the equilibrium flash vaporization temperature curve for the blended stock is drawn. By referring to Figure 6, it will be seen that the equilibrium flash vaporization temperature for the initial stock when 72% is vaporized is 705° F. When 60% of the blended stock is vaporized, the temperature will be 825° F. 75

It will appear from the foregoing that even though the equilibrium flash vaporization temperature for the blended stock is higher than the equilibrium flash vaporization temperature of the virgin stock, yet cracking will be prevented in the latter case, due to the shorter time the stock is subjected to heat in the tower. This follows because there is a larger quantity of heavier ends in the mixture, and the velocity of liquid flow through the high temperature zones in the process is increased.

More particularly, referring now to Figure 1, a crude oil passes from storage through line 1 and is pumped by pump 2 through heat exchanger 3, through line 4, through heat exchanger 5, through line 6, through heat exchanger 7, through line 8, through heat exchanger 9, through line 10, through heat exchanger 11, through line 12, through heat exchanger 13, through line 14, to mixing tank 15. Heavy crude, or a top crude containing a quantity of desired heavy ends, is pumped from line 16 by pump 17 through line 18, into the mixing tank in which it is thoroughly blended with the virgin crude. The mixture passes from the mixing tank 15 through line 19, and is pumped by pump 20, through line 21 through the convection heat bank 22 of the atmospheric tube still 23, through radiant heat bank 24, through transfer line 25, into the atmospheric fractionating tower 26. Gasoline vapors are removed overhead through line 27, passed through heat exchanger 3 and condenser 28, into separator 29. The condensate is withdrawn from the separator 29 and passes into reflux tank 30 from which reflux is pumped by pump 31 through reflux line 32. Gasoline is pumped through line 33 to storage. A kerosene cut is withdrawn through line 34 and a gas oil cut is withdrawn through line 35. The mixture thus denuded of gasoline, kerosene and some of its gas oil is withdrawn from the bottom of atmospheric tower 26 through line 36 and is passed through convection heat bank 37 of the vacuum tube still 38. Then it passes through the radiantly heated bank 39 of the tube still 38 and through transfer line 40 to the vacuum fractionating tower 41. A booster or vacuum jet 42 discharging into a barometric condenser 43 maintains the vacuum tower under sub-atmospheric pressure. The oil vapors are withdrawn from the vacuum tower through line 44, and pass through heat exchangers 7 and 45 to run tank 46 from which lubricating fraction "A" is withdrawn through line 47. A portion of this lubricating oil fraction is returned to the tower through line 48 as reflux. Lubricating fraction "B" is withdrawn from the tower, passed through heat exchangers 9 and 48, through line 49, to run tank 50, whence it is pumped by pump 51 through line 52 to storage. Similarly, lubricating oil fraction "C" is withdrawn from the tower through heat exchangers 11 and 53, and passed through line 54 to run tank 55 whence it is pumped by pump 56 through line 57 to storage. The heaviest fraction of reflux condensate and unvaporized tar is withdrawn from the tower through line 58 by pump 59, and is passed through heat exchangers 13 and 60, through line 61 to storage.

The above operation is that which takes place during the two stage operation. To show the efficiency of my invention, I give herewith the yields obtained when running a virgin crude deficient in heavy ends and a mixture of 80% of

crude and 20% of top crude containing heavy ends:

	Virgin crude	Mixture— 80 percent virgin crude and 20 per- cent topped crude	5
	Percent	Percent	10
Gasoline	43.5	36.2	10
Kerosene	6.2	5.2	
Gas oil	19.8	17.4	
Lube "A"	13.4	18.5	
Lube "B"	2.5	3.5	
Lube "C"	7.2	10.0	
Tar	5.4	7.4	
Loss	2.0	1.8	15
	100.00	100.00	

The topped crude which was added in the above example contained the following pertinent fractions:

	Per cent	20
Gas oil	5.0	
Lube A	47.9	
Lube B	6.6	25
Lube C	22.5	
Tar	15.0	
Loss	3.0	
Total	100.0	30

It is to be remembered, however, that the pertinent fractions in a topped crude to be added will vary according to the degree to which it is topped, or the amount of light material removed. The pertinent fractions will also vary in topped crudes produced from different virgin crudes. The degree to which the topped crude must be reduced is predetermined by the laboratory determinations of the desired blended crude as set forth herein.

It will be observed that the yields of lubricating oil fractions "A", "B" and "C" have been materially increased. Furthermore, it is found that the quality of the lubricating oil fractions is better and that there is little danger of cracking.

In the example given above, when the virgin crude was being processed, the transfer temperature from the atmospheric tube still to the atmospheric tower, that is, the temperature in line 25, was 550° F., the reduced crude passing through line 36 to the vacuum still was 30.2% of the total charge. The transfer temperature from the vacuum tube still to the vacuum tower was 800° F.

In the case of the mixture, the transfer temperature from the atmospheric tube still to the atmospheric tower, that is, through line 25, was 500° F., and the material passing from the atmospheric tower to the vacuum tube still was 41.2% of the total charge.

Referring now to Figure 2, crude oil is charged through line 1 and pumped by pump 2 through condenser 3, through line 4, through heat exchanger 5, through line 6, through heat exchanger 7, through line 8, through heat exchanger 9, through line 10, through heat exchanger 11, through line 12, through heat exchanger 13, through line 14 to mixing tank 15. Topped crude or a heavy crude rich in heavy fractions, is pumped from line 16 by pump 17, through line 18 to the mixing tank 15 in which it is thoroughly admixed with the preheated virgin crude.

The mixture is pumped from mixing tank 15 through line 19, through pump 20, through line 75

21, through convection heat bank 22 and radiant heat bank 24 of atmospheric tube still 23, through the transfer line 25 into the atmospheric, single flash fractionating tower 26. Gasoline is removed overhead through line 27 and passes through heat exchangers 3 and 28 to separator 29. Gasoline is added from separator 29 and passes into the reflux tank 30, from which reflux is pumped by pump 31 through reflux line 32. A portion of the gasoline from separator 29 is pumped through line 33 to storage. A kerosene fraction is withdrawn from the tower through line 34, and a gas oil fraction is withdrawn from the tower through line 35. A lubricating oil fraction "A" is cooled and withdrawn from the tower through line 47. A lubricating oil fraction "B" is withdrawn from the tower through line 52, and lubricating oil fraction "C" is withdrawn from the tower through line 57. The heaviest fraction of reflux condensate, commonly called "tar", is withdrawn from the tower through line 61.

In order to show the improved results I obtain in practice, the following table is given:

	Virgin crude	Mixture—80 percent virgin crude and 20 percent topped crude
	Percent	Percent
Gasolene.....	42.0	35.0
Kerosene.....	6.3	5.3
Gas oil.....	20.5	17.9
Lube "A".....	15.7	21.0
Lube "B".....	2.2	3.0
Lube "C".....	7.3	9.9
Tar.....	5.0	6.7
Loss.....	1.0	1.2
	100.00	100.00

It will be observed that the yields of lubricating oil fractions "A", "B" and "C" are increased by my invention.

In the example given just above, 20% of top crude was added to 80% of virgin crude. The transfer temperature in line 25 in the case of the virgin crude was 620° F. In the case of the blended crude, in which the equilibrium flash vaporization temperature of the mixture was higher than that of the virgin crude, the transfer temperature was 870° F.

The topped crude in the above cases was a bottom cut having 5% of gas oil.

It will be seen that I have accomplished the objects of my invention. I am enabled to employ a given unit to obtain uniform results by way of yields and quality from charging stocks normally unadapted to be processed in the unit. A refiner is enabled to convert portions of cheap fuel oils into valuable lubricating oils.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. The method of increasing lubricating oil fraction yields from a crude hydrocarbon oil, including the steps of adding a topped crude containing a larger proportion of lubricating oil fractions than is contained in the crude oil to be distilled, to the crude oil to be distilled, in order to raise the equilibrium flash vaporization temperature of the lubricating distillate oils to be obtained, heating the mixture thus formed, to distillation temperature, fractionating the heated mixture in a fractionating zone, and withdrawing at least two lubricating oil stocks from the fractionating zone at different points therefrom, said stocks having had their equilibrium flash vaporization temperature raised by the addition of said topped crude.

2. A method of fractionating crude oils to obtain lubricating oil stocks, in which a crude oil is heated to vaporize a portion thereof and the heated oil and vapors fractionated in a fractionating zone, increasing lubricating oil yields without cracking the lubricating oils desired to be recovered, by raising the equilibrium flash vaporization temperature of the oil to be distilled, by adding a hydrocarbon oil mixture containing a larger proportion of lubricating oil fractions than is contained in the oil to be distilled to reduce the carrying effect of the light, more volatile components in the oil to be distilled, and to increase the velocity of the liquid flow through the fractionating zone.

3. A process of increasing lubricating oil yields in the fractional distillation of crude hydrocarbon oils, including the steps of raising the equilibrium flash vaporization temperature of the oil to be distilled by adding thereto a sufficient quantity of topped crude containing a larger proportion of lubricating oil fractions than is contained in the crude oil to be distilled, heating the oil of raised equilibrium flash vaporization temperature, fractionating the heated oil in a first fractionating zone, removing gas oil and lower boiling reflux condensate fractions from the first fractionating zone, separately removing the residual oil from the first fractionating zone, heating the residual oil, fractionating the residual oil in a second fractionating zone at reduced pressure, and withdrawing at least two lubricating oil stocks from said second fractionating zone at different points in said fractionating zone, said stocks having had their equilibrium flash vaporization temperatures raised by the addition of said topped oil.

4. In a process of fractionating crude oils to obtain lubricating oil stocks in which a crude oil is heated to vaporize a portion thereof, and the heated oil and vapors fractionated in a fractionating zone, the steps of admixing with the crude oil before the heating step a sufficient quantity of topped crude containing a larger proportion of lubricating oil fractions than is contained in the oil to be distilled in order to raise the equilibrium flash vaporization temperature of the oil being distilled, whereby to increase the velocity of flow in the process and to avoid substantial cracking of the desired lubricating oil fractions.

FRED G. FELLOWS.
